Primary Examiner — Marie D. Fast Horse(74) *Attorney, Agent, or Firm* — Muncy, Geissler, Olds & Lowe, P.C.(57) **CLAIM**

The ornamental design for an electronic sensing payment device, as shown and described.

DESCRIPTION

FIG. 1 is a perspective view of an electronic sensing payment device showing my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.

1 Claim, 8 Drawing Sheets---
